8 Claims. (Cl. 235—194)

This invention relates to analog multipliers and more particularly to an improved analog multiplier for multiplying the instantaneous values of two electrical signals.

Analog multipliers, such as employed in analog computers, have in the past employed elaborate circuitry, for instance, servo mechanisms, function generators, or phase modulators. These prior art analog computers have two limitations, namely, the signals to be multiplied must be D.C. or slowly varying A.C. signals and the bandwidth is restricted.

An object of this invention is the provision of simple circuitry to multiply the instantaneous values of two varying electrical signals whose operation is independent of the frequency range of the signals, at least within the frequency range limitation of the external components of the circuit.

Another object of this invention is to provide a transistor circuit to multiply the instantaneous value of two varying electrical signals and provide a voltage output proportional to either the instantaneous product of the two signals or a time average product of the two signals.

A feature of this invention is the provision of a transistor amplifier of the complementary symmetry transistor type wherein the signal controlling the collector current to be proportional thereto is coupled to the collector electrode to provide the product of the instantaneous value of the two electrical signals or the time average product thereof.

The above-mentioned and other features and objects of this invention will become more apparent by reference to the following description taken in conjunction with the accompanying drawings, in which:

FIG. 1 is a schematic diagram of an embodiment of an analog multiplier according to this invention; and

FIG. 2 is a series of curves illustrating the multiplier characteristics of the embodiment of FIG. 1.

The operation of the multiplier in accordance with this invention is based on the particular characteristic of transistors, namely, that the transconductance, g_m , is directly proportional to the collector current. This may be illustrated as follows. Theoretically

$$g_m = \frac{q}{kT} (I_c - I_{cs}) \quad (1)$$

where q is equal to the magnitude of electronic charge, k is equal to the Boltzmann constant (1.381×10^{-23} joule/°K.), T equals the temperature in degree Kelvin, I_c equals the collector current, and I_{cs} equals the inverse collector saturation current. For the practical operation of the analog multiplier of this invention, the inverse collector saturation current, I_{cs} , is negligible and, thus, the Equation 1 will reduce to

$$g_m = k_b I_c \quad (2)$$

where k_b is equal to q/kT which is equal to 38.4 at a room temperature of 25° C. (centigrade). If it is desired to perform the multiplication of two signals, of the alternating type and obtain a product of these two signals, $v_1 v_2$, a transistor amplifier is constructed in which the input signal applied to the input electrode is proportional to v_1 and the collector current is rendered proportional to v_2 . The resulting output voltage will contain a term proportional to $v_1 v_2$.

Referring to FIG. 1, there is illustrated therein a schematic diagram of a preferred embodiment of an analog multiplier according to this invention. This multiplier includes two complementary symmetry transistors 30 and 31 biased for class B operation with a common collector terminal 32. The two voltages or signals v_1 and v_2 to be multiplied are applied respectively to the base electrodes of transistors 30 and 31 through coupling condensers 33 and 34 and to the collector electrodes of transistors 30 and 41 through resistor 35. In this circuit arrangement the collector current of transistors 30 and 31 is varied by the voltage v_2 applied to the common collector terminal 32 and the output voltage will include a voltage proportional to $v_1 v_2$. When this is applied to an integrator circuit 36, the time average of the product $v_1 v_2$ is obtained. If the input voltages v_1 and v_2 are sinusoidal, the output voltage at terminal 37 will be non-zero if, and only if, these two input voltages v_1 and v_2 have the same frequency. The output may be expressed as follows starting with Equation 3.

$$v_{out} = g_m R_L v_{in} \quad (3)$$

$$v_{out} = \frac{q}{kT} R_L I_c v_{in} \quad (4)$$

Letting $v_{in} = V_{b0} + v_1$ where V_{b0} is a constant and equal to the bias voltage,

$$I_c = \frac{v_2}{R_L + r_d} \quad (5)$$

where r_d is equal to collector resistance. Then

$$v_{out} = \frac{q R_L}{kT} \left(\frac{V_{b0} v_2}{R_L + r_d} + \frac{v_1 v_2}{R_L + r_d} \right) \quad (6)$$

$$\frac{1}{T} \int v_{out} dt = \frac{q R_L}{kT} \left(\frac{v_1 v_2 \cos \phi}{2(R_L + r_d)} \right) \quad (7)$$

where V_1 and V_2 are the amplitudes of the two voltages and ϕ is their relative phase difference. It should be noted that the resulting voltage is generally very small due to the fact that r_d is large.

In the case in which the voltage v_2 is not of the alternating type, the output from terminal 32 must be processed through a difference amplifier, the other input to the difference amplifier being the signal v_2 in order to cancel out the term proportional to v_2 from the output signal v_{out} . Difference amplifiers suitable for this application are well known in the art and therefore a detailed discussion thereof is not deemed necessary herein.

The operation of the multiplier is valid within certain finite ranges of the input voltages. An example of linearity of multiplier operation is shown in FIG. 2 where the output voltage is plotted versus one of v_1 and v_2 , keeping the other signal constant. As illustrated v_1 is maintained constant and v_2 is varied. The correct operation of the multiplier of FIG. 1 corresponds to the ranges of v_1 and v_2 for which the output is represented by the solid straight lines with slope linearly proportional to the variable parameter.

The component values for the reduction to practice of FIG. 1 are listed below.

- $R_1 = 500$ K ohms
- $R_2 = 15$ K ohms
- $R_3 = 1.6$ K ohms
- $R_4 = 100$ K ohms
- $R_5 = 6.8$ K ohms
- $R_6 = 1.6$ K ohms
- $R_7 = 10$ K ohms
- $R_8 = 100$ K ohms
- $C_1 = 27$ microfarads
- $C_2 = 27$ microfarads
- $C_3 = 1$ microfarad

$+B=10$ volts

$-B=10$ volts

Transistor 30=2N1415

Transistor 31=2N1694

While I have described above the principles of my invention in connection with specific apparatus, it is to be clearly understood that this description is made only by way of example and not as a limitation to the scope of my invention as set forth in the objects thereof and in the accompanying claims.

I claim:

1. An analog multiplier for two electrical signals comprising:
  - a transistor amplifier including two complementary symmetry transistors, each having at least base, emitter and collector electrodes;
  - first means to couple a first of said signals to said base electrode of each transistor, the signal appearing at each of said base electrodes being substantially the same;
  - second means to couple the second of said signals to said collector electrodes of each transistor to control the collector current of said transistors to be proportional to said second signal; and
  - output means coupled to said collector electrode of each of said transistors to provide an output voltage proportional to the product of said two signals.
2. The analog multiplier according to claim 1 wherein said output means includes an integrator coupled to said collector electrodes of each of said transistors to provide an output voltage proportional to the time average product of said two signals.
3. The analog multiplier according to claim 2 wherein said integrator comprises:

a first resistor coupled to the collector electrodes of said transistors; and

a capacitor coupled to said first resistor, the output signal being obtained at the connection between said first resistor and said capacitor.

4. The analog multiplier according to claim 1 wherein said first means comprises first and second capacitors coupling said first signal to said base electrodes of each of said transistors, respectively.
5. The analog multiplier according to claim 1 wherein said second means comprises a second resistor coupling said second signal to said collector electrodes of said transistors.
6. The analog multiplier according to claim 1 further comprising means for biasing said transistor for class AB operation.
7. The analog multiplier according to claim 1 further comprising:
  - means coupling said collector electrodes together; and
  - means coupling said emitter electrodes together.
8. The analog multiplier according to claim 7 wherein said collector electrodes are directly connected together and wherein said emitter electrodes are directly connected together.
